UNITED STATES PATENT OFFICE.

GIUSEPPE SILVESTRO BARBERIS, OF SALUGGIA, ITALY.

APPARATUS FOR PRINTING VIGNETTED PHOTOGRAPHS.

1,126,346.

Specification of Letters Patent.

Patented Jan. 26, 1915.

Application filed March 28, 1914. Serial No. 827,869.

To all whom it may concern:

Be it known that I, GIUSEPPE SILVESTRO BARBERIS, a subject of the King of Italy, residing at Saluggia, Italy, have invented 5 certain new and useful Improvements in Apparatus for Printing Vignetted Photographs, of which the following is a specification.

It is known that in order to facilitate 10 the execution of vignetted photographs and portraits in particular, it has been proposed to employ apparatus in which a flat vignetter, presenting the desired aperture, is clamped between two frames and its distance from the negative to be copied is 15 regulated in modifying the position of the said frames relatively to the negative. In order to obtain good results it is, however, necessary in certain cases to be able to arrange 20 the elements of the vignetter in different planes corresponding with different zones of the negative, because, in portraits for example, the negative is generally speaking more transparent at the bust than in the background and consequently the inner edge of the vignetter toward the bust should be located at a smaller distance from the negative than the edge of the vignetter surrounding the head if it be desired to obtain 25 uniform vignetting throughout the entire contour. In accordance with the present invention this object is attained by employing a plurality of metal, cardboard, or the like plates for the formation of the 30 vignetter, these plates being cut out in such a manner as to permit of forming, by the combination of their edges, the desired aperture in the vignetter and of mounting these plates in an apparatus which not only permits 35 of displacing the said plates parallel to the negative but also of arranging them in different positions and planes.

The invention is illustrated in the accompanying drawing, in which:—

45 Figure 1 shows diagrammatically the formation of a complete vignetter; Fig. 2 is a vertical section showing the position of the several plates relatively to the negative; Fig. 3 shows the position of the plates in forming a vignetter with a small aperture; Fig. 4 is a cross section showing an apparatus fitted to the ordinary printing frame and permitting of forming a vignetter of the kind illustrated in the preceding figures; 50 Fig. 5 is an external view of a corner; Fig. 6 is a plan, partly in section, of one of the 55 sides; Fig. 7 shows a detail of a modified type; Fig. 8 is a sectional plan of the corner in Fig. 7; Fig. 9 illustrates another type of apparatus in section; Fig. 10 is a section 60 on the line A—B in Fig. 9; Fig. 11 is a plan thereof showing a corner in section, and Figs. 12 to 15 illustrate constructional details in section for rendering the apparatus 65 independent of the printing frame and for fitting it thereon.

Vignetters are known which comprise a plate having at its center an aperture of the desired form and having a second plate 70 adapted to be arranged above the most transparent zone of the negative at a lesser distance therefrom than the first plate.

According to this invention in order to form with a limited number of parts any vignetter with the usual apertures, no matter what is the size of the photograph to be vignetted, I have adopted the arrangement illustrated in Figs. 1-3, in which by means of plates 6 and by suitably changing the head plates 4, 4¹ in such a manner as to form 75 the desired size of semicircular opening 5, it is possible to pass from a large opening (Fig. 1) to the very small opening shown in Fig. 3 because the outline of the lateral plates 6 is such as to form an adequate connection between the edges of the head plates. In Fig. 3 the head plates used are indicated by the reference numbers 34, 34¹. Furthermore any of the independent plates constituting the vignetter may be arranged at different distances from the negative according 80 to the transparency of the corresponding zone of the negative. Figs. 1 and 2 illustrate also the application of auxiliary strips 9 which may be of cardboard or of any other 85 material such as opaque cloth or the like and adapted to be considerably displaced upon the heads of the printing frame; these strips serve to cover the portion of the negative which would not be covered by the plates 90 4, 4¹. These strips 9 may have lateral extensions 9¹ or not, as desired, in which latter case they are clamped solely by the corresponding bars to the shortest sides of the printing frame and this arrangement facilitates 95 their manipulation. The lateral edges of the strips 9 enter channels 22¹ which each of the bars 13 may be provided with on its inner edge; this serves to prevent the passage of light (Fig. 10). Fig. 2 shows the 100 application of these auxiliary strips 9 which can be arranged in the same plane as the 105 110

other plates or in a different plane provided that the rear edges of the latter are covered; this figure also shows that the said strips 9 can be bent back upon the head of the printing frame so that they do not constitute an obstacle to its support. In order to realize in practice this arrangement of plates intended to form in front of the negative an aperture of the desired form and dimensions, it is necessary to provide an apparatus which can be combined with or united to the printing frame. This apparatus is broadly constituted by four uprights projecting at the four corners of the printing frame and between which are mounted in such a manner as to be capable of vertical displacement, parallel and superposed strips of wood which can be clamped to the frame so that they retain the several plates referred to above in the desired position and immovable relatively to each other.

A constructional form of the apparatus is illustrated in Figs. 4 to 6, where four uprights 10 are fixed to angle pieces 11 which are themselves fixed at their lower part to the corners of an ordinary printing frame 12, and at their upper part to a frame 14. Between the uprights 10 and the angle pieces 11 the wooden strips 13 are held; their ends are shaped in such a manner that they are able to slide along the uprights 10. The frame 14 may be provided with set screws 15 by means of which it is possible to clamp the strips 13 between them and upon the printing frame. The strips 14¹ serving to screen the opening remaining between the upper wooden strips and the frame are fixed to this frame 14 in the space not occupied by the angle pieces 11. The projections 14² may be used to fix a plate of ground glass or the like for diffusing the light. A resilient frame 17 may be arranged upon the upper plane of the frame 14 by engaging it in projections constituted by the heads of screws 16; this resilient frame is formed by curved flexible strips and by means of which it is possible to clamp upon the frame 14 one or more sheets of parchment paper or the like with the same object of diffusing the light. The shape assumed by this frame when it is desired to disengage it from its stops is represented in broken lines.

The modification illustrated in Figs. 7 and 8 differs from the foregoing type merely by the fact that the angle piece 11 is exclusively fixed to the upper frame 14 and at its lower part has an arm 11¹ for retaining the strips 13 which are guided by means of screws 18 which at the same time serve to fix the apparatus as a whole to the printing frame. In order to clamp the strips 13 to one another and to the printing frame 12, the set screws 15 can be replaced by springs 19 pivoted at 20 and adapted to be turned to act upon a series of strips 13 or removed

therefrom to leave these strips free. In this embodiment of the invention the resilient frame 17 is connected by means of a hinge 21 to one of the sides of the frame 14, while it can be engaged at the other extremity in appropriate catches.

In the embodiment of the invention illustrated in Figs. 9 to 11 the uprights by means of which the strips 13 are guided are merely constituted by the screws 22 fixed in the frame of the printing frame and the means for clamping these strips together are constituted by springs 23 each of which is pivoted beneath the head of one of the screws 22 on each side, their other extremity being adapted to be engaged beneath the head of the screw on the same side. In this manner a device similar to those previously described is obtained, with the difference that the upper frame 14 is rendered independent of the rest of the apparatus and can be connected with the frame 12 by means of resilient arms 24 which can be engaged in stops or hooks 25 fixed to the printing frame. It is also possible to render the apparatus completely independent of the printing frame by forming by means of angle pieces 11 a rigid cage in which the strips 13 are held; this cage can be provided with means for connecting it with the printing frame. These means may consist of a lower frame 26 and set screws 27 engaged on the outer wall of the printing frame (Figs. 12 and 13) or of a frame provided with holes 28 in which projections 29 fixed to the printing frame are engaged by means of a bayonet joint, fitting being insured by the provision of a stop 30 (Figs. 14 and 15). In any event with this apparatus it is possible to arrange the strips 13, the strips 9, the head plates 4, 4¹ and the lateral plates, for forming the desired vignette at any desired distance from the negative, by locking these several elements by clamping the strips 13 by means of screws, springs or equivalent means. Finally it is possible to realize with the greatest simplicity all the conditions for obtaining the best vignetting effects, because paper or ground glass can be provided on the upper frame for diffusing the light and these diffusion means can be speedily replaced or removed. It is also possible to print by arranging the parchment paper which may be supported in a frame of cardboard or other appropriate material, directly in contact with the upper plates forming the vignette or else between strips arranged higher up. In this manner by simultaneously providing the parchment paper or the like above the frame 14, owing to the interval existing between these two sheets a condition is obtained which has been found to be the best for diffusing the light, especially when printing is being effected in a very bright or artificial light.

When employing developing paper or plates it is advisable to cover the four sides of the apparatus with a covering of black cloth or the like, to prevent any possibility 5 of light penetrating through the strips 13 between which the plates, which as a whole constitute the vignette, are clamped.

What I claim as my invention and desire 10 to secure by United States Letters Patent is:—

1. Apparatus for printing vignetted photographs comprising a plurality of independent plates intended to form by their combination the required aperture, a plurality 15 of bars parallel to the four sides of the frame intended to clamp between them said plates, means for mounting said bars on the frame of the printing frame, so that they are able to move a little in a direction perpendicular to the plane of the printing frame and means for clamping said bars on each other and on the printing frame.

2. Apparatus for printing vignetted photographs comprising a plurality of independent plates intended to form by their combination the required aperture, a plurality 25 of bars parallel to the four sides of the printing frame intended to clamp between them said plates and provided with slots on their inner edges, means for mounting said bars on the frame of the printing frame so that they are able to move a little in a direction perpendicular to the plane of the printing frame and means for clamping said bars on each other and on the printing frame.

3. Apparatus for printing vignetted photographs comprising a plurality of independent plates intended to form by their combination the required aperture, a plurality 30 of bars parallel to the four sides of

the printing frame between which the independent plates are inserted, means for connecting said bars to each other with play, means for clamping said bars on each other 45 and means for securing the whole apparatus on the printing frame.

4. Apparatus for printing vignetted photographs comprising a plurality of independent plates intended to form by their 50 combination the required aperture, a plurality of bars parallel to the four sides of the printing frame between which the independent plates are inserted, angle pieces fixed to the corners of the printing frame 55 and inclosing the ends of said bars, a frame secured to said angle pieces having means for clamping said bars on each other and on the printing frame, and means on said frame for affixing on it a pellucid screen. 60

5. Apparatus for printing vignetted photographs comprising a plurality of independent plates intended to form by their combination the required apertures, a plurality 65 of bars parallel to the four sides of the printing frame between which the independent plates are inserted, means for mounting said bars on the printing frame so that they are able to move in a direction perpendicular to the frame of the printing 70 frame, means for clamping said bars on each other and on said frame, a frame arranged on said bars intended to hold a pellucid screen and a flexible and resilient frame on said frame for arranging said pellucid 75 screen in the required position.

In testimony whereof I affix my signature in presence of two witnesses.

GIUSEPPE SILVESTRO BARBERIS.
